UNITED STATES PATENT OFFICE.

JOSEPH EBERT JOHNSON, OF LOUISVILLE, KENTUCKY.

ORTHODONTIC APPLIANCE.

1,369,665.

Specification of Letters Patent.

Patented Feb. 22, 1921.

Application filed December 21, 1920. Serial No. 432,251.

To all whom it may concern:

Be it known that I, JOSEPH EBERT JOHNSON, a citizen of the United States, and a resident of Louisville, in the county of Jefferson and State of Kentucky, have invented certain new and useful Improvements in Orthodontic Appliances, of which the following is a specification.

The present invention relates to orthodontic appliances, and has for its object to provide a device of this character which is of extremely simple and durable construction, which positively holds and constrains the arch-bar to perform its orthodontic function, which does not interfere with occlusion and does not annoy or discomfort the wearer, which is universal in action and application and which is easy and inexpensive to manufacture.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a plan view of the invention embodied in an orthodontic appliance;

Fig. 2 is a detail view in perspective of the anchor band in position on the molar, the arch bar and interlocking means;

Fig. 3 is a vertical detail view in perspective of the lock lug and the anchor band;

Fig. 4 is a fragmentary detail view in perspective of the saddle clamp of the arch bar;

Fig. 5 is a detail perspective view of the key; and

Fig. 6 is a detail view in plan of a slightly modified form of interlocking means.

Referring to the drawings wherein for the sake of illustration is shown the preferred embodiment of the invention, it will be seen that the invention is adapted for use with the orthodontic appliance of the lingual type. The arch-bar of this type of appliance designated at 10, is provided with curved rear end portions 11 adapted to be releasably secured to the anchor bands 12 arranged as usual on the molars by the interlocking means designated generally at 13. The interlocking means 13 is positioned on the inner side of its anchor band 12, as clearly shown in Fig. 1.

The interlocking means comprises a lock

lug 15 soldered or otherwise secured to the anchor band. The lock lug 15 is tapered longitudinally that is, it is tapered transversely of the anchor band and its lateral faces 60 designated at 16 are under cut or inwardly inclined, as shown in the drawings. A key opening 17 extends transversely through the lock lug and the upper surface of the lock lug adjacent the anchor band is provided 65 with a key slot 18. A saddle clamp 19 is integrally formed with or otherwise secured to the arch bar 10 at each of its rear curved end portions 11. The saddle clamp is provided with a channel 20, the lateral walls of which 70 are inclined, as shown at 21 correspondingly with the inclined lateral faces of the lock lug, and this channel is also tapered longitudinally corresponding with the lock lug whereby when the saddle is mounted on 75 the lock lug the inclined walls of the channel will be snugly and slidably engaged with the lateral faces of the lock lug. The coaction of the under cut lateral faces and the inclined walls prevents lateral displacement 80 of the saddle from the lock lug and the taper of the lock lug and the saddle prevents endwise displacement in one direction. For the purpose of preventing endwise displacement in the other direction the 85 saddle is provided with key openings 22 and a key slot 23 adapted to be aligned respectively with the key opening and key slot of the lock lug. A key 24 of malleable metal is inserted in the aligned key openings 17 and 90 22 of the lock lug and saddle clamp when they are assembled, and is then bent upwardly and is seated in the key grooves 18 and 23 of the lock lug and saddle clamp and is burnished in position therein.

In practice, it is obvious that the invention is especially adapted for use with orthodontic appliances of the lingual type and with such appliances may be readily and securely fastened in proper position upon the 100 anchor bands and maintained fastened against displacement irrespective of the action of food or other forces tending to disassociate the element from the appliance. The appliance does not interfere with occlusion, and is so positioned that it will not afford discomfort or annoyance to the wearer.

I claim:

1. In an orthodontic appliance of the character described, in combination with an arch-bar having curved rear end portions and anchor bands, interlocking means for secur-

- ing each curved rear end portion to its anchor band comprising a tapered lock lug secured to the anchor band and having under-cut lateral faces and provided with a 5 key opening therein and a key slot in its upper face, a saddle clamp having a tapered channel provided with inclined walls corresponding to the under-cut lateral faces of the lock lug and having key openings and a 10 key slot adapted to be aligned respectively with the key openings and key slot of the lock lug and a malleable key inserted in the key openings and bent to be seated in the key slot and burnished therein.
- 15 2. In an orthodontic appliance of the character described, means for securing the arch-bar to the anchor band including a lock lug having under-cut lateral faces and provided with a key opening and a key slot, 20 a saddle clamp adapted to be mounted on said lock lug and having a channel pro-

vided with inclined walls adapted to engage the under-cut faces of the lock lug and having a key opening and a key slot adapted to be aligned with the key opening and the key 25 slot of the lock lug and a malleable key arranged in the key opening and having its end seated in the key slot and burnished therein.

3. In an orthodontic appliance, means for 30 securing the arch bar to the anchor band including a tapered lock lug having under-cut lateral faces, a saddle clamp adapted to be mounted on said lock lug and having a tapered channel provided with inclined walls 35 adapted to engage the under-cut faces of the lock lug, and a malleable key adapted to cooperate with the lock lug and the saddle clamp to maintain the same in locked position.

JOSEPH EBERT JOHNSON.
